UNITED STATES PATENT OFFICE

2,267,207

TROLLEY DUCT COLLECTOR SYSTEM

Charles C. Martin, Cleveland Heights, Ohio, assignor to David Round & Son, Garfield Heights, Ohio, a firm

Application March 29, 1939, Serial No. 264,790

6 Claims. (Cl. 191—23)

This invention, as indicated, relates to a trolley duct collector system. More particularly, it comprises a trolley and a trolley trackway, such trackway having current conducting elements built into the structure and protected against accidental contact with adjacent material. It involves details of construction of the stationary and movable conducting elements, and also includes the application of such construction to a crane or similar apparatus.

The principal object of the present invention is to provide an improved current conducting system for movable units of apparatus.

Another object of the invention is to provide stationary and movable current conducting units protected from danger of accidental contact and having high capacity and efficiency.

Another object of the invention is to provide a trolley duct collector system which is constructed of a minimum number of parts, and which is economical to manufacture and install, and which is especially adapted for easy inspection and low cost of maintenance.

Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain mechanism embodying the invention, such disclosed means constituting, however, but several of various forms in which the principle of the invention may be used.

In said annexed drawing:

Fig. 1 is a longitudinal side elevation of a trackway and carriage embodying the principles of the invention, parts being broken away to illustrate details thereof;

Fig. 2 is a transverse sectional view of the structure shown in Fig. 1 as seen along the line 2—2, Fig. 1, looking in the direction of the arrows;

Fig. 3 is an enlarged sectional detail of one of the collector arms as seen along the line 3—3, shown in Fig. 1, looking in the direction of the arrows;

Fig. 4 is a view similar to Fig. 3 as seen along the line 4—4, shown in Fig. 1 looking in the direction of the arrows; and

Fig. 5 is a diagrammatic view illustrating a crane hoist provided with a plurality of trolley ducts for supplying current thereto and controlling the position thereof.

As is clearly shown in Figs. 1 and 2, the collec-

tor duct system comprises a supporting plate 1, providing an overhead or ceiling support and having at spaced intervals standards in the form of sleeves 2 bearing against a trackway plate 3 and held in rigid relation thereto by means of a bolt 4 with its head 5 engaged in a recess formed in an insulating block 7, such block bearing against the under face of the trackway plate 3. The block 7 also serves as a means of support for

10 a conductor tube 8 held in firm position beneath the same by means of a pair of channel clamping elements 9, 10, drawn toward each other by means of a clamping bolt 11, preferably extending through an aperture in said block. The supporting plate 1 is preferably provided at intervals with angle bracket members 12 preferably secured by welding to the under side of said supporting plate, and supporting at their lower ends elongated angle plates 13, upon the inwardly turned flanges of which are mounted at intervals insulating blocks 14, upon the upper edges of which are supported conductor tubes 15, 16, respectively, such tubes being held firmly in position by means of channel clamping elements 17, 18, similar in construction to the clamping elements 9, 10, heretofore described and held in position by means of bolts 19.

It will be noted from the construction above described that a central trackway for the wheels 30 of a trolley is provided by the plate 3 heretofore mentioned, beneath which one conductor tube 8 is supported and that a partially enclosed conduit or duct construction is formed by means of the angle bracket 12 and the angle plates 13, the angle plates also serving to carry additional conductor tubes 15, 16, in spaced relation at either side of the central conductor tube 8 and slightly above the same, and clamped upon insulator blocks in similar manner.

40 The collector trolley 21 illustrated in Figs. 1 and 2 comprises a pair of side plates 22, 23, held in spaced relation by means of a pair of spacing blocks 24, 25, and a spacing sleeve 26 through all of which suitable securing bolts 27 are engaged. 45 At an intermediate point between the spacing sleeve 26 and the inner spacing block 24 an insulated collector arm spring supporting block 28 is provided, said block being secured at its ends by bolts 29 extending through inwardly projecting supporting plates 30, 31, spaced from each other and secured to the respective side plates 22, 23.

The trolley harp or collector arm 32 is preferably formed of brass, or some suitable conducting metal, and comprises a forked contact arm struc-

ture apertured near its free end to receive the axle 33 upon which the contact roller or wheel 34 is rotatably supported. At the opposite end of the forked contact arm structure it is pivotally supported upon an insulating sleeve 35 engaged over an axle 36 supported in aligned apertures in the side plates 22, 23, of the trolley structure. Insulating washers 37, 38, serve to hold the forked contact arm in a substantially central position between the side plates of the trolley carriage. At an intermediate position the forked contact arm is provided with a spring centering abutment in the form of a T-shaped element 41 held in position by a bolt 42. The depending portion of the T-shaped element engages within a coiled spring 43, the lower end of said spring being received within a recess 44 provided centrally of the insulating block 28, heretofore described. At the pivoted end of the forked contact arm suitable contact lugs 45 are provided, against which the terminal elements 46 of conducting cables 47 may be secured by screws 48, or other suitable connecting means. The structure just described comprises the central lower conductor assembly which bears against the lower conductor tube 8. The trolley carriage at each of its respective upper inner corners is provided with flanged track wheels 51 running on ball bearings 52 supported on stub axles 53.

The contact arms for the two outermost conductor tubes 15, 16, are substantially identical in construction, the right-hand arm 54 being complementary to the left-hand arm 55. The pivoted contact arms are supported upon suitable insulating sleeves 56 on stub axles 57, and have insulating washers 58, 59. At their free ends contacting arms carry contact wheels 61 supported on stub shafts 62, and at an intermediate point on their inner faces have secured thereto by suitable fastening elements, such as screws 63, insulating blocks 64, such blocks having recesses 65 in their upper faces, within which coil springs 66 are engaged, such coil springs bearing at their free ends against projecting plates 67 secured to the side plates of the trolley carriage adjacent their central upper edges. The contact arms have projecting lugs 68, against which terminals 69 on the conducting cables 71 are adapted to be secured by means of screws 72, or other fastening elements.

When assembled with an overhead hoist the trolley duct system may assume the form shown diagrammatically in Fig. 5 wherein the crane 81 has a transverse I-beam 82, upon which the hoist trolley 83 travels, such trolley having the hoisting mechanism and motor 84 in a casing 85 beneath said trackway. The hoisting cable 86 and hook 87 extend downwardly beneath the casing, and the control lines 88, 89, are within convenient reach of the operator. The trolley duct 91 may be used as the current supply line extending to the controller within the casing 85, and being distributed thence to the hoist motor and selectively to the crane motor, the crane control passing through the three-phase collector duct 92 on the opposite side of the trackway. In order to keep conductor trolley carriages 93, 94, in the respective trackways at a point closely adjacent the hoist mechanism, a lateral arm 95 is carried by the trolley 83, and is connected by means of short chain lengths 96, 97, with the respective conductor trolleys 93, 94.

If desired, a motor for traversing the hoist trolley along the transverse I-beam may be provided and included in the controls above de-

scribed. It will be noted that both the crane construction and the trolley duct system are formed of a minimum number of parts, and that the mechanism is at all times readily accessible in that it provides for large open spaces through which access may be had to the conductor tubes and the supporting structure. At the same time the maximum of safety for the crane conducting elements is provided since such conducting elements are held in a protected position within the duct structure and accidental contact with adjacent objects is prevented by the insulated structural elements outwardly of the large conductor tubes.

15 While the electrical system illustrated is for three-phase alternating current it is by no means intended to restrict the invention to any particular type of generation and transmission of current as the equipment may be designed for 20 use with any of various types of current, including direct current, as well as single phase, two phase and three phase alternating current. For direct current and single phase alternating current one of the three conductor tubes illustrated 25 may be dispensed with, preferably the one beneath the central trackway. For two phase alternating current four conductors are required, and two of these may be placed below the central trackway, and two inner collector arms similar 30 to the outer collector arms 54, 55, may be used in place of the single central collector arm 32. Appropriate changes in the equipment, such as motors and controllers, will be required in harmony with the type of current available at the 35 point of installation.

The tubular current conductors, it will be noted, have high transmission capacity, and at the same time are sufficiently rigid to be free of sagging or stretching in use. The method of mounting the 40 conductors produces a firm grip upon the same, but permits easy inspection and replacement, if required.

Other modes of applying the principle of my 45 invention may be employed instead of those explained, change being made as regards the structure herein disclosed, provided the means stated by any of the following claims or the equivalent of such stated means be employed.

I therefore particularly point out and distinctly claim as my invention:

1. An apparatus of the character described, having in combination a stationary current conducting structure providing a central trackway and a central conductor element beneath the same, lateral supports providing a skeletonized guard rail structure in spaced relation around said trackway, conductor elements each removably clamped to separate insulating blocks, supported within said enclosed area, a movable current collector unit engaged upon said trackway and extending around the same, and the central conductor element, on its under side, and contact means supported on said collector unit for resilient engagement with said respective conductors.

65 2. An apparatus of the character described, having in combination a stationary current conducting structure providing a central trackway and a central conductor element beneath the same, lateral supports providing a skeletonized guard rail structure in spaced relation around said trackway and carrying conductor elements in lateral spaced relation at each side of said trackway, a movable current collector unit engaged upon said trackway and extending around the same, and the central conductor element, on its

under side, and contact means supported on said collector unit for resilient engagement with said respective conductors.

3. An apparatus of the character described, having in combination a stationary current conducting structure providing a central trackway, a central conductor element beneath the same, lateral supports around said trackway and carrying additional conductor elements in spaced relation thereto, a movable current collector unit engaged upon said trackway and extending around the same, and the central conductor element, on its underside, and contact means supported by and at the sides of said collector unit for resilient engagement with said respective conductors.

4. An apparatus of the character described, having in combination an elongated supporting member of plate-like form, bracket members secured thereto at spaced intervals, inwardly extending angle plates supported by said bracket members, conductor elements supported on said inwardly turned angle plates in insulated relation thereto, a trackway supported centrally of said supporting structure, a conductor element supported by said trackway in insulated relation immediately beneath the same, a current collector carriage movably supported on said trackway and having depending side plates extending below said trackway, a current collector member secured intermediate said side plates beneath said central conductor for resilient contact therewith, collector members secured to the side

plates in the horizontal plane of said trackway for engagement with the lateral conductor elements, and conducting cables for carrying current from each of said conducting elements.

5. A three-phase current conducting system for apparatus having a predetermined range of movement which comprises a central supporting member, a central trackway beneath said supporting member and a conductor element supported by said trackway in insulated relation beneath the same, an insulated conductor element at either side of said trackway secured to inwardly turned angle plates, brackets connecting said plates with said main support at intervals, a current collecting carriage mounted on said trackway, resiliently supported collector arms mounted at either side of said carriage and within the central lower portion of the same for contact with said respective conductor elements.

20 6. A trolley duct collector system comprising an elongated base member, a plurality of supports depending from said base member and holding a trackway in spaced relation thereto, and also holding at least one insulated conductor member beneath said trackway, a plurality of bracket members secured at spaced intervals to said base member, elongated inwardly projecting supporting members secured to the lower ends of said brackets and conductor members supported in insulated relation against lateral contact upon said inwardly projecting members.

CHARLES C. MARTIN.
